UNITED STATES PATENT OFFICE.

WILLIAM INMAN, OF MILWAUKEE, WISCONSIN, ASSIGNOR TO THE PSARSKI DYEING MACHINE COMPANY, OF CLEVELAND, OHIO, A CORPORATION OF OHIO.

DYEING-MACHINE.

1,181,314.

Specification of Letters Patent.

Patented May 2, 1916.

Application filed June 13, 1913. Serial No. 773,550.

To all whom it may concern:

Be it known that I, WILLIAM INMAN, a subject of the King of England, residing at Milwaukee, in the county of Milwaukee and 5 State of Wisconsin, have invented certain new and useful Improvements in Dyeing-Machines, of which the following is a specification.

This invention relates generally to dyeing machines and particularly to that type of such devices wherein the material is located in a tank or vat within a mass forming and liquor supplying member which is substantially bowl shaped and is adapted to 10 hold the mass in the proper shape against a cover having a central isolated discharge, said mass forming and liquor distributing member being provided with openings which, together with the discharge openings in the cover, set up direct paths of travel for the dye liquor, which are substantially equal throughout the entire mass, that 15 is, a straight line from any point in the liquor supply or of the bowl to the nearest point of liquor discharge is equal to every 20 other path, this being accomplished by the bowl shaped bottom with the openings isolated in the center of the cover.

The circulation set up by the mass forming and liquor supplying means and the central isolated discharge in the cover causes the mass, when wet, to be compacted by the flow of the dye liquor along lines coincident with the natural lines of shrinkage 25 of the mass.

The invention may be further briefly summarized as consisting in the construction and combination of parts hereinafter set forth in the following description, 30 drawings and claims.

Referring to the drawings, Figure 1 is a side elevation of a dyeing apparatus showing the tank distributing member and cover in section; Fig. 2 is a bottom plan view of 35 the cover; Fig. 3 is a top plan view of the bowl shaped mass forming and liquor supplying member; Fig. 4 is a sectional view of a portion of a vat with cover and distributing member showing auxiliary discharge openings in the portion of the cover between the main discharge and the periphery thereof; and Fig. 5 is a bottom plan view of the cover.

In carrying out the invention any preferred form and construction of machine

may be employed so long as it possesses the necessary characteristics, but I have shown one arrangement in the drawings which is effective in operation and in such embodiment 1 represents a suitable tank provided with an inlet opening 2 at the bottom and preferably at the center connected by suitable piping with the outlet of a pump 3 which is adapted to draw liquor through a suitable pipe 4 from an opening 5 at a point near the upper edge or through an opening 6 in the bottom of the tank. During the dyeing operation, however, it is preferable to have the circulation established in such a manner that the dye liquor flows in at the bottom of the tank through the pipe 2 at the center while the discharge takes place through the opening 5. This means for the circulation of dye liquor may be of any preferred type, the present form being merely one arrangement which is well known in the art.

The tank 1 is provided on its interior with an inwardly projecting flange 7 having a gasket groove therein for receiving a gasket 8 of fibrous material which will be suitable for forming a gasket. Resting upon the gasket is a cover 9 which is preferably imperforate except for a central spot which is provided with discharge perforations 10. The cover is braced by suitable webbing 11 which is cut away at 12 above the perforations to allow predischARGE of the liquor and to cause the discharge to be substantially uniform throughout its area. Engaging the cover is a suitable ring 13 held down by clips 14 in a well known manner this feature of the casing being relatively unimportant, as any securing means for the cover will answer the purpose.

Secured to the flange 7 is the mass forming and liquor distributing member 15 which has a substantially flat area 16 corresponding to the area of the discharge in the cover. The remaining portion or the curved side in cross section is of arc shape, the arc thereof having for a center the outer edge of the discharge and in cases where perforations or holes are used for the discharge the center of the outer row of openings or holes is the center of the arc described by any transverse section of the side of the mass forming and distributing member. This member is secured to the flange by means of screws or any other preferred manner, the

main feature being the idea of providing an isolated discharge, or in other words, a discharge having an imperforate area about the same with the mass forming and liquor supplying member which forms and holds the mass so that equal paths of travel will lead from the supply opening in this member to the discharge. In order to prevent the batch from shifting within the machine, 10 I provide the distributing member 15 with an upwardly extending rod 17 so that it will project into the mass and hold it from shifting about after it is shrunk.

In the modifications shown in Figs. 4 and 15 5, the cover 9 is provided with auxiliary discharge openings 18 which are fewer in number and smaller than the main discharge openings whereby there is a slight release of liquor and pressure between the main discharge and the periphery. The mass forming and liquor distributing member is bowl shaped, that is, it is substantially semi-spherical, although in the drawings it is shown flattened at the bottom to correspond 20 with the discharge. It may, however, be arranged in the form of a perfect half-sphere. The working parts of the machine, that is, the tank, cover and distributing member, may be inverted so that the lines 25 of flow are downward and toward the center in place of upward toward the center.

Having described my invention, I claim:

1. In a dyeing machine, a receptacle forming a dyeing chamber, a closure for 35 said receptacle substantially flat and having a main central isolated discharge, a foraminous mass forming and liquor supplying member for forming the mass to establish substantially equal paths of travel from 40 each point of liquor supply to its nearest point of liquor discharge, and means for circulating the dye liquor.

2. In a dyeing machine, a receptacle forming a dyeing chamber, mass confining 45 means comprising a substantially flat member with a main central isolated discharge, a foraminous mass shaping and liquor supplying member for forming the mass to establish substantially equal paths of travel 50 from each point of liquor supply to its nearest point of liquor discharge, and means for circulating the dye liquor.

3. In a dyeing machine, a tank, a cover having a central discharge, and a mass 55 forming and liquor supplying member

shaping the mass and holding it in a manner to establish equal paths of travel for the dye liquor through the mass to the discharge, and means for circulating the dye liquor.

60

4. In a dyeing machine, a tank, a cover having a central foraminous discharge, and a mass forming and liquor supplying member of bowl shape and of a construction such that the paths of travel of the dye 65 liquor from all points of liquor supply to the nearest liquor discharge are substantially equal.

5. In a dyeing machine, a tank, a cover having a central foraminous discharge, and 70 a foraminous mass forming and liquor supplying member substantially bowl shaped having a flat portion co-extensive with the discharge and an arc-shaped side, the distance from the discharge in the cover to the 75 edge of the mass forming and liquor supplying member and the radius of the side of such member and the distance from the flat bottom to the discharge being all substantially equal, and means for circulating 80 the dye liquor.

6. In a dyeing machine, a tank, a cover having a central foraminous discharge, and a foraminous mass forming and liquor supplying member of bowl shape with a flat 85 bottom co-extensive with the discharge and an arc-shaped side, the radius of the arc and the distance of the flat portion of the bottom being substantially equal to the distance from the outer periphery of the discharge to the edge of the bowl-shaped mass forming and liquor supplying member.

7. In a dyeing machine, a receptacle forming a dyeing chamber, mass confining means comprising a substantially flat member with 90 a main central isolated discharge and an auxiliary discharge, a foraminous mass shaping and liquor supplying member for forming the mass to establish substantially equal paths of travel from each point of 95 liquor supply to its nearest main point of liquor discharge, and means for circulating the dye liquor.

In testimony whereof I affix my signature in presence of two witnesses as follows.

WILLIAM INMAN.
